UNITED STATES PATENT OFFICE.

WILLIAM C. DICK, OF FREEPORT, ILLINOIS, ASSIGNOR OF THREE-FOURTHS TO HENRY C. EICH, OF FREEPORT, ILLINOIS.

ADJUSTING DEVICE FOR LOCOMOTIVE DRIVING-BOXES.

No. 877,059.

Specification of Letters Patent.

Patented Jan. 21, 1908.

Application filed June 5, 1907. Serial No. 377,396.

To all whom it may concern:

Be it known that I, WILLIAM C. DICK, a citizen of the United States, residing at Freeport, in the county of Stephenson and State 5 of Illinois, have invented a new and useful Adjusting Device for Locomotive Driving-Boxes, of which the following is a specification.

The invention relates to improvements in 10 adjusting devices for locomotive driving boxes.

The object of the present invention is to improve the construction of the means for adjusting locomotive driving boxes, and to provide 15 a simple and efficient construction of increased strength and durability adapted to permit the wedge of a locomotive driving box to be adjusted from the outside of the locomotive, without the danger and inconvenience 20 of crawling beneath the locomotive to effect such adjustment.

A further object of the invention is to provide adjusting means of this character capable of enabling lost motion between the forward and rearward pedestal jaws to be readily 25 taken up and provided with means for preventing the adjusting devices from becoming rapidly worn.

With these and other objects in view, the 30 invention consists in the construction and novel combination of parts hereinafter fully described, illustrated in the accompanying drawing, and pointed out in the claims hereto appended; it being understood that various 35 changes in the form, proportion, size and minor details of construction, within the scope of the claims, may be resorted to without departing from the spirit or sacrificing any of the advantages of the invention.

40 In the drawing:—Figure 1 is a side view of a portion of a locomotive frame provided with driving box adjusting means, constructed in accordance with this invention. Fig. 2 is a sectional view, taken longitudinally of 45 the locomotive frame. Fig. 3 is a vertical sectional view, taken substantially on the line $x-x$ of Fig. 2. Fig. 4 is a detail perspective view of the adjustable wedge. Fig. 5 is a detail perspective view of the yoke. Fig. 50 6 is a detail view of the pedestal braces.

Like numerals of reference designate corresponding parts in all the figures of the drawing.

1 designates a portion of a locomotive 55 frame, provided with pedestal jaws 2 and 3,

and adapted to receive a driving box of any preferred construction. A shoe 4 of the ordinary construction is fitted against the jaw 2 and is provided at opposite sides with flanges 5 to prevent lateral movement. The 60 shoe 4 is retained in place by a screw 6, piercing the pedestal jaw and engaging a threaded perforation of the shoe. The other pedestal jaw 3 receives a wedge 7, adapted to be adjusted to take up lost motion 65 between the pedestal jaws, and provided at opposite sides with flanges 8 to prevent lateral motion. The wedge is provided at its lower end with an opening 9, and it has a slot 10 at the bottom of the opening. The opening 70 9 receives a head 11 of a yoke 12, which surrounds a thimble pedestal brace 13. The head 11, which is connected with the upper end of the yoke by a neck 14, is preferably circular in cross section and the opening 9, 75 which receives the head, is also circular in cross section to conform to the configuration of the same. The neck 14 fits in the slot 10, which communicates with the opening 9. By this construction, the yoke is interlocked 80 with the lower end of the wedge and is engaged with and disengaged from the wedge by a relative transverse movement, when the parts are detached from the locomotive frame.

85 The yoke is provided at its lower end with a threaded opening 15 for the reception of an adjusting screw 16, having a lower polygonal wrench-receiving portion 17 and provided at its upper end with a head 18, 90 which engages a socket 19 of the pedestal brace 13. The pedestal brace 13, which consists of a sleeve or thimble, extends across the space between the lower ends of the pedestal jaws and is arranged on a bolt 20, 95 which pierces the jaws, as clearly illustrated in Fig. 2 of the drawing. The bolt 20 is provided at one end with a head, and has a pair of nuts 21 at its threaded end, which are prevented from becoming lost by a key 22. 100

The socket of the pedestal brace is located in the vertical plane of the wedge, and it is formed by a pair of depending substantially L-shaped walls or flanges 23, connected at their inner ends by a transverse wall 24, the 105 outer end of the socket being open and the inner end being closed, but both ends of the socket may be open, as the wall 24 simply strengthens the construction. The socket, which is substantially T-shaped in cross 110

section, receives the smooth round head of the screw and an adjacent smooth portion 25.

The adjusting screw is provided with a washer 26, arranged beneath the head and bearing against the flanges 23. The washer is tapped to enable it to be passed over the threaded portion of the adjusting screw, and it is designed to be of a metal slightly softer than the head of the screw and the pedestal 10 brace, so that it will receive the wear, and prevent either the screw or the walls of the socket from becoming worn. Also the washer by resting upon the bottom portions of the side walls or flanges 23 spans the space between the same and forms a continuous bearing for the head of the screw. When the washer becomes worn, it may be readily removed and replaced by a new washer.

The adjusting screw receives a lock nut 27, 20 arranged to engage the lower end of the yoke to prevent the screw from accidentally unscrewing. By means of a ratchet wrench, the screw 16 and the wedge may be conveniently adjusted from the outside of a 25 locomotive, without getting beneath the same, and as the yoke surrounds and receives the pedestal braces, it is unnecessary to pierce the latter for the adjusting screw.

Having thus fully described my invention, 30 what I claim as new and desire to secure by Letters Patent, is:—

1. In a device of the class described, the combination of a driving box adjusting wedge, a pedestal brace, a yoke surrounding the pedestal brace and interlocked with the wedge, and an adjusting screw interlocked with the pedestal brace and engaging the yoke for raising and lowering the wedge.

2. In a device of the class described, the 40 combination of a driving box adjusting wedge, a pedestal brace, a yoke surrounding the pedestal brace and having its upper end detachably interlocked with the lower end of the wedge, and a screw for adjusting the yoke.

3. In a device of the class described, the 45 combination with pedestal jaws, of a pedestal brace connecting the jaws, an adjustable wedge, a yoke surrounding the pedestal brace and connected at the top with the wedge, said yoke and wedge having interfitting engaging parts detachable from each other by relative movement longitudinally of the pedestal brace, and means for adjusting the movement.

4. In a device of the class described, the 55 combination of a wedge provided with an opening and having a slot communicating therewith, a pedestal brace, a yoke surround-

ing the pedestal brace and provided at the top with a head detachably fitted in the 60 opening of the wedge and connected with the yoke by a neck portion, which is arranged in the said slot, and adjusting means for the yoke.

5. In a device of the class described, the 65 combination of a wedge provided with an opening, a pedestal brace having a socket at the bottom, a yoke surrounding the pedestal brace and provided at the top with a projecting portion fitting in the opening of the wedge, 70 and an adjusting screw engaging the bottom of the yoke and having a head fitted in the socket of the pedestal brace.

6. In a device of the class described, the 75 combination of a wedge, a pedestal brace provided at the bottom with a socket, a yoke surrounding the pedestal brace and detachably interlocked at the top with the wedge, and an adjusting screw engaging the bottom of the yoke and provided with a head fitted 80 in the socket, whereby it is detachably interlocked with the brace.

7. In a device of the class described, the 85 combination of a wedge, a pedestal brace provided at the bottom with a socket consisting of spaced substantially L-shaped flanges, and a transverse wall connecting the inner ends of the flanges, a yoke surrounding the pedestal brace and detachably interlocked with the wedge, and an adjusting screw engaging the bottom of the yoke and having a head fitted in the socket.

8. In a device of the class described, the 90 combination of a wedge, a pedestal brace provided with a socket composed of spaced walls having supporting bottom portions, a yoke connected with the wedge and surrounding the pedestal brace, a screw engaging the bottom of the yoke and having its head fitted in the socket, and a washer fitted on the adjusting screw beneath the head and spanning the space between the side walls of the socket.

9. In a device of the class described, the 95 combination of a wedge, a pedestal brace, a yoke surrounding the pedestal brace and connected with the wedge at the lower end thereof, and an adjusting screw interlocked with the pedestal brace and engaging the bottom of the yoke.

In testimony, that I claim the foregoing as 100 my own, I have hereto affixed my signature in the presence of two witnesses.

WILLIAM C. DICK.
